UNITED STATES PATENT OFFICE.

ANGEVINE NORTHUP, OF GREENPORT, NEW YORK.

GEAR-BODY.

1,191,907.

Specification of Letters Patent. Patented July 18, 1916.

Application filed November 18, 1915. Serial No. 62,189.

To all whom it may concern:

Be it known that I, ANGEVINE NORTHUP, a citizen of the United States, residing at Greenport, Long Island, in the county of 5 Suffolk and State of New York, have invented certain new and useful Improvements in Gear-Bodies; and I do declare the following to be a full, clear, and exact description of the invention, such as will enable others skilled in the art to which it appertains to make and use the same.

This invention relates to new and useful improvements in gears, and more particularly to the body construction of said gears.

15 The primary object of the invention is to provide a very efficient gear which is especially adapted for use on power transmitting devices on motor boats, etc., and which is provided with means for silencing the 20 ringing noise which is very noticeable ordinarily during the operation of the gearing.

A further object of the invention is to provide a device of this character which is simple and durable in construction, inexpensive to manufacture, and one which will be 25 very efficient in operation.

With these and numerous other objects in view my invention consists of the novel features of construction, combination and arrangement of parts which will be hereinafter referred to and more particularly pointed out in the specification and claim.

In the accompanying drawings:—Figure 1 is a central vertical longitudinal section; 35 Fig. 2 is a transverse section taken on the line 2—2 of Fig. 1.

In describing my invention I shall refer to the drawings in which similar reference characters designate corresponding parts 40 throughout the several views and in which the numeral 1 designates one of the outside portions of my improved gear, which consists of a circular plate having a plurality of teeth 2 on its outer periphery, and having 45 projecting laterally from one side of the same and centrally positioned with respect thereto, a short stub shaft 3. The side of the plate opposite the projecting shaft 3 has formed therein a countersunk portion 4 for a purpose to be hereinafter more fully 50 described. This side of the plate 1 is provided with a plurality of apertures 5 and 6', disposed around the same and extending transversely therethrough. The apertures 55 5 through the same are disposed adjacent the outer periphery, while the apertures 4

are positioned adjacent the center of the said plate or gear.

Positioned on the stub shaft 3 is a correspondingly shaped plate 6 to the plate 1, 60 which is adapted to form the other side of the complete gear when assembled. This plate 6 has formed thereon peripheral teeth 7 and disposed transversely therethrough a plurality of openings 8 and 8', which are 65 adapted for alinement with the openings 5 and 5' through the plate 1. The plate 6 is provided with a centrally disposed aperture 9 which is adapted to engage the stub shaft 3 as clearly shown in Fig. 1 of the drawings. 70

Interposed between the inner surfaces of the plates 1 and 6, is a correspondingly shaped raw hide annulus 10, which has formed on its outer periphery, teeth 11. This raw hide annulus 10 is provided with 75 a plurality of apertures 12 and 13 which are adapted for alinement with the apertures 5 and 8, and 5' and 8' respectively in the adjacent plates. The annulus 11 is provided with a central aperture 14 which is adapted 80 to engage the stub shaft 3, so that the same may slide thereon. When these parts are positioned as clearly shown in Fig. 1 of the drawings, and the apertures in the plates and annulus are all disposed in alinement 85 with one another, a plurality of fastening members, preferably rivets 15, are disposed through the alining apertures 5, 12 and 8 to securely hold the above mentioned parts in position. A plurality of bolts 16 are adapted to be positioned through the alining apertures 4, 13 and 8', and the outer ends of 90 these bolts 16 project outwardly past the outer surface of the plate 1 so that they may securely hold a coupling member 17 in engagement therewith, as clearly shown in 95 Fig. 1 of the drawings.

From the above description it will be obvious that to assemble this gear, it is only necessary to take the plate 1 and slide on 100 the stub shaft that projects laterally therefrom, first the annulus 11, and then the plate 6, and secure these parts together as above described, whereby the gear will be assembled. This forms a very simple and efficient 105 gear especially applicable for use as a power transmitting gear on motor boats, motor vehicles, etc. The raw hide annulus that is interposed between the side plates 1 and 6 of the gear will act as a silencer, while the gear 110 is in operation, and prevent the ringing sound usually caused by the meshing of the

different gears. This will be found to be a great advantage when the gear is used for the purposes above stated, as it will obviate the greater part of the noise incidental to 5 changing of the gears and the operation of the same.

From the foregoing description of the construction of my improved device and the manner of applying the same to use, the operation thereof will be readily understood 10 and it will be seen that I have provided a simple, inexpensive, and efficient means for carrying out the objects of this invention.

The gears of this device may be either 15 straight or beveled, or of any size required for the character of work on which they are used.

I claim:—

A device of the class described comprising 20 a circular plate having teeth formed on its periphery, an integral centrally disposed solid stub shaft projecting from the inner side of the plate, said plate having a centrally disposed recess in its outer side, a 25 raw hide annulus centrally apertured and

correspondingly shaped to said plate positioned on the shaft and lying flush with the inner side of the plate, an additional plate correspondingly shaped to said annulus disposed on the shaft and lying flush against 30 the outer side of the same, said plates and annulus having annular spaced series of apertures therethrough adjacent the periphery and axis of the same, fastening members positioned through the apertures 35 adjacent the periphery to secure the parts together, and additional fastening members positioned through the apertures adjacent the axis and projecting through the recess in the outer side of said plate whereby a coupling member may be securely engaged therewith.

In testimony whereof I have hereunto set my hand in presence of two subscribing witnesses.

ANGEVINE NORTHUP.
